UNITED STATES PATENT OFFICE

96,488

DESIGN FOR A RADIATOR

Raymond Loewy, New York, N. Y., assignor to
Sears, Roebuck and Co., Chicago, Ill., a corpora-
tion of New York

Application January 4, 1935, Serial No. 54,727

Term of patent 7 years

To all whom it may concern:

Be it known that I, Raymond Loewy, a citizen of France, residing at New York city, in the county of New York and State of New York, have invented a new, original, and ornamental Design for a Radiator, of which the following is a specification, reference being had to the accompanying drawing, forming part thereof.

The figure is a perspective view of a radiator showing my new design and composed of separately cast sections coacting to present the appearance of a cabinet, the design being especially

characterized by the provision in the upper part of the front wall of the structure of vertically elongated parallel air discharge openings with the front edges of vertically spaced fins terminating horizontally in rearwardly offset relation to the plane of said openings, substantially as shown.

I claim:

The ornamental design for a radiator substantially as shown and described.

RAYMOND LOEWY.
